UNITED STATES PATENT OFFICE.

SAMUEL A. STEWART, OF LONGTON, KANSAS.

PLOW.

1,068,184.

Specification of Letters Patent.

Patented July 22, 1913.

Application filed July 16, 1912. Serial No. 709,702.

To all whom it may concern:

Be it known that I, SAMUEL A. STEWART, a citizen of the United States, residing at Longton, in the county of Elk and State of Kansas, have invented certain new and useful Improvements in Plows, of which the following is a specification.

This invention relates to improvements in tongueless plows, and has for its object to 10 provide a device in the nature of an attachment, whereby the draft animals will guide the plow during its operation.

The further object of the invention is to so construct a clevis that the same will 15 operate the caster wheel to assist in guiding the plow.

With these and other objects in view, the invention consists in the construction and novel combination of parts hereinafter fully 20 described, illustrated in the accompanying drawings, and pointed out in the claims hereto appended; it being understood that various changes in the form, proportion, size and minor details of construction within 25 the scope of the claims, may be resorted to without departing from the spirit of the invention or sacrificing any of the advantages of the invention.

In the drawings: Figure 1 is a side elevation of the device. Fig. 2 is a top plan view of the device, showing the same applied to a beamed tongueless plow. Fig. 3 is a detail sectional view of the clevis.

Referring to the drawing, the numeral 1 35 designates the plow beam formed from metal, to which the clevis 2 is pivotally connected.

The clevis 2 consists of a perforated bar 3 having an arm 4 which extends at right 40 angles. Formed in the outer end of said bar is a perforation 5, the purpose of which will appear later. Passing through the inner end of the bar 3 is a pin 3', by which the clevis is pivotally connected to the beam.

To permit attachment of the clevis to beams of different sizes a jaw 4' is provided, one 45 end of which is formed with a slot 5' for slidably engaging the bar 3, while the other end is provided with a perforation 2' for 50 similarly engaging the pin 3'. To hold the jaw 4' in an adjusted position, a bolt 1' is passed through a perforation formed therein which registers with any one of the perforations of the bar 3.

55 A pair of blocks 6 and 7 are provided

and are adapted to be clamped upon the beam 1 by bolts 8, the clamping block 6 having secured thereto and extending outwardly a bracket 9, said bracket being for the purpose of pivotally supporting a lever 60 10, the opposite ends of which being provided with perforations 11 and 12. The lever 10 is curved at its inner end to prevent a dead center.

It is obvious that the bracket 9 may be 65 secured on the block 7 so that the lever 10 will be supported upon either side of the beam 1, and further that the clevis be so formed that the arm 4 may be extended from either side of the beam, as shown 70 in dotted lines in Fig. 2, thus permitting the device to be applied to either side of the beam, as the occasion may require.

It will be noted that the lever 10 is pivotally mounted nearer the inner end thereof, the rear end of the link 13 being pivotally engaged in the perforation 11 of said lever, while the front end of the link is similarly connected in the perforation 5 of the arm 4.

Suitably secured to the curved end of the beam 1 is a caster wheel 15, the pintle 16 of which is rigidly connected to the inner end of the arm 17, said arm having a perforation 18 formed in its outer end, and 85 in which is pivotally connected one end of a rod 19. The other end of said rod is similarly connected in the perforation 12 of the lever 10.

From this construction it will be seen 90 that when the draft strain upon the clevis is directed to the right, the caster wheel 15 will be swung to assist in guiding the plow in the same direction, the direction of travel of the caster wheel being reversed upon the 95 draft strain being directed to the left.

What is claimed is:—

The combination with a wheel plow, of a beam supported thereby, a clevis pivotally connected to the outer end of the beam, 100 an arm connected to the clevis and arranged at right angles thereto, blocks clamped upon the beam and adapted to be moved longitudinally thereof for adjustment, a bracket carried by one of the blocks, a lever pivotally connected to the bracket, a link having its front end pivotally connected to the arm and its rear ends similarly connected to the lever near the outer end thereof, a 105 pintle secured to the rear end of the beam, 110

a caster wheel mounted on the pintle, an arm rigidly connected at its inner end to the pintle, a rod pivotally connecting the outer end of said arm and the inner end of 5 the lever whereby when the clevis is swung upon its pivot the caster wheel will be operated to guide the plow.

In testimony whereof, I affix my signature, in presence of two witnesses.

SAMUEL A. STEWART.
